NOVELTY YARN AND METHOD OF
PRODUCING IT

Alfred A. Forster, Drexel Hill, Pa., assignor to
Clifton Yarn Mills, Clifton Heights, Pa., a corporation of Pennsylvania

Application May 3, 1940, Serial No. 333,084

5 Claims. (Cl. 57—144)

This invention relates to novelty yarns such as are used to create fancy effects (as distinguished from definite design patterns) in fabrics woven or knitted from them, and also to methods of producing such yarns.

The chief aim of my invention is to make it possible to predetermine variegated irregular striped effects and the like in fabrics more especially intended for use as dress materials or draping. This objective I realize in practice, as hereinafter more fully disclosed, through provision of a compounded novelty yarn in which a plurality of cover or sheathing threads are wrapped about spaced sections of a colored or otherwise contrasting core thread, with said sheathing threads intertwisted in the intervening intervals.

Another aim of my invention is to make it possible to expeditiously and cheaply produce in quantity, novelty yarn characterized as above. This desideratum I realize as also more fully set forth hereinafter, through provision of a simple method which can be practiced with the aid of ordinary types of twisting machines.

Other objects and attendant advantages will appear from the following detailed description of the attached drawings, wherein Fig. 1 shows a fragment of my improved novelty yarn on an enlarged scale.

Fig. 2 is a similar view on a still larger scale showing a fragment of the core thread.

Fig. 3 shows the partially completed thread with one of the sheathing or cover threads wrapped about the core thread.

Fig. 4 is a view like Fig. 1 of the completed thread drawn to a scale corresponding to that of Figs. 2 and 3.

Figs. 5 and 6 are diagrammatic views in vertical section of two twisting machines suitably organized to carry out the method for commercially producing the yarn.

As delineated in Fig. 1 and on a larger scale in Fig. 4, my improved novelty yarn Y comprises two cover threads 10 and 11 which form a sheath around section 12a of a base or core thread 12 separated by substantial skip intervals 13 which are where the aforesaid cover threads are intertwisted. For convenience of exemplification, the cover strand 10 (which, for convenience I term the "effect" thread), may be composed of two doubled ends of 50/1 bright white spun rayon, the second sheathing strand 11 of a fine end of 50 Den. bright white rayon, and the core thread 12 of colored 100 Den. "Union resist" acetate thread. After its formation in a manner presently de-

scribed, the yarn may be dyed in any desired color (other than that of the core), the dye selected being such as will not affect the original color of the core sections 12a. Thus, in the finished exemplified yarn the sheathing threads 10 and 11 will contrast with the core sections 12a. It is to be understood, however, that threads of other sizes and materials may be employed, depending upon the effect desired in the finished product. Thus, by way of further illustration, the sheathing threads 10 and 11, may be of altogether different materials such as real silk and cotton which will be affected to different extents by the dye employed and therefore be of correspondingly different shades of the same color in the finished yarn. Still other effects may be had by utilizing more than two sheathing yarns either of the same or different materials. As a further variation, the cover threads may be wrapped in opposite directions instead of in the same direction as shown herein by way of illustration.

The yarn may be conveniently formed in two operations which are respectively illustrated in Figs. 3 and 4. In the first operation, the sheathing thread 10 is wrapped about the core thread 12 (of which a fragment is shown in Fig. 2) after the manner illustrated in Fig. 3. In the second step, the other sheathing thread 11 is wound about the partially completed yarn Y' of Fig. 3, and tension is applied at the same time, so that the more fragile core thread 12 is strained and broken at intervals after the manner shown in Fig. 4.

The two steps or stages of the method just described can be conveniently carried out with the aid of two twisting machines such as diagrammatically illustrated in Figs. 5 and 6. The machine shown in Fig. 5 has two sets of pinch rollers 15, 16 and 17, 18 by which the core thread 12 and sheath thread 10 are drawn from separate sources of supply indicated at 19 and 20 respectively, and a revolving spool or spindle 21 which receives the partially completed thread Y'. By means of connecting gearing conventionally indicated by the broken link circles 22, 23 and 24, the rolls 17, 18 are driven at a somewhat faster rate than the rolls 15 and 16 with the result that the core thread 12 is maintained taut and the sheathing thread 10 wrapped about it by the rotation of the spool 21 as the two threads pass the twisting point at 25. In the second step or phase of the operation, the spool 21 of the partially completed yarn Y' is mounted, together with a supply spool 26 of the other cover thread 11, in the twisting machine shown in Fig. 6. This

twisting machine, like that of Fig. 5 has two sets of pinch rolls 27, 28 and 29, 30 which act respectively upon the thread 11 and the partially completed yarn Y'. By means of the intermeshing spur gears conventionally indicated at 31, 32 and 33, the rolls 29, 30 are driven at a somewhat faster rate than the rolls 27, 28. As a result the partially completed thread Y' is stretched up to the breaking point of the core yarn 12 in the interval between the pinch rolls 27, 28 and 29, 30. The stretching takes place between the eye 34 and the pinch point 37 of the rolls 27, 28, while the repeating rupture of the more fragile core thread 12 occurs between said eye 34 and the pinch point 38 of the rolls 29, 30. The sheathing thread 11 meets with the thread Y' at the eye 34 and is doubled with the latter thread at the pinch point 38 of the rolls 29 and 30, the doubling twist being induced by rotation of the collecting spool 35.

The above described apparatus is of course to be considered merely as representative of other means by which my improved novelty yarn may be produced in quantity for commercial purposes.

Having thus described my invention, I claim:

1. Novelty yarn in which a plurality of cover or sheathing threads surround spaced sections of a core thread, and in which the cover or sheath-

ing threads are intertwined in the intervals intervening the core thread sections.

2. Novelty yarn according to claim 1, in which the core and the cover or sheathing threads are of different colors.

3. Novelty yarn according to claim 1, in which the core and the cover or sheathing yarns are of different materials.

4. The method of producing novelty yarn with alternate thick and thin segments which comprises wrapping a plurality of non-elastic cover or sheathing threads about a relatively fragile non-elastic core thread, and incidently straining the core thread to cause it to rupture periodically, and to cause elongation of the intervening twists of the sheathing threads.

5. The method of producing novelty yarn with alternate thick and thin segments which comprises wrapping a non-elastic cover or sheathing thread about a relatively fragile non-elastic core thread to form the partially completed yarn, and then wrapping another non-elastic sheathing or cover thread about the partially completed yarn and incidently straining the core thread to cause it to rupture periodically, and to cause elongation of the intervening twists of the sheathing threads.

ALFRED A. FORSTER.
